ART OF PRODUCING LOW BOILING POINT HYDROCARBON OILS FROM HIGH BOILING POINT HYDROCARBON OILS

Application filed February 10, 1930. Serial No. 427,216.

The present invention relates to improvements in the manufacture of gasoline or motor fuel from heavier hydrocarbon oils by cracking or decomposition in the vapor phase, more particularly for the production of motor fuel products in the gasoline boiling point range having anti-knock properties equivalent to those secured by the addition of tetrachethyl lead to virgin Mid-Continent gasoline in proportions of at least 1.5 cc. and preferably 2 cc. or higher per gallon.

In vapor phase operations as hitherto conducted, the production of a motor fuel product of suitable anti-knock characteristics has been attended with various difficulties, such as low gasoline yields as compared with ordinary liquid phase cracking operations, excessive gas losses, coking troubles and the like, as a result of which various expedients in operation have been introduced, for example, the introduction of inert gases, in the system as heat carriers, the use of catalysts and of fillers for the heating tubes or members, and the like in the effort to obviate these difficulties. In accordance with the present invention, a gasoline or motor fuel product of the desired anti-knock characteristics may be secured with yields commensurate with those obtainable in liquid phase cracking processes, with relatively low gas and tar losses, and without such specific operating means as the introduction of gases, the use of special cores in the heating elements or the use of catalysts. The invention will be fully understood from the following description illustrated by the accompanying drawings, in which:

Figure 1 is a diagrammatic view of apparatus suitable for carrying the invention into effect;

Fig. 2 is a diagrammatic view of a modified form of apparatus suitable for carrying out the invention;

Fig. 3 is a sectional diagrammatic view of the enlarged reaction chamber of Fig. 2;

Fig. 4 is a sectional diagrammatic view of the fractionating column of Fig. 2; and

Fig. 5 is a chart indicating suitable temperature gradients in the heating operation in carrying out the invention.

Referring more particularly to Fig. 1 of the drawings, the numeral 5 designates the heating furnace, which may be of any suitable type. In the form illustrated, it is constructed with the combustion chamber 6 as a modified Dutch oven, the combustion gases being carried upward through a vertical shaft 7 to the flue 8. The heating tubes 9 are disposed horizontally in the furnace shaft 7, providing initial heating and vaporizing sections 10 and 10^a in which little cracking occurs, and a section 11 in which the rest of the vaporizing and most of the cracking takes place. The oil supplied to the heating coil enters the coil through the pipe 12, passes through the initial heating section 10 and then through the pipe 13 to section 10^a and through the cracking section 11. The oil is subjected to rapid heating in section 10^a, which in the form of furnace illustrated, is subjected to radiant heat. From the cracking section 11 the vapors pass through line 14 provided with pressure release valve and arranged so that they discharge tangentially into the separator tower 16 below the liquid level. A body of condensed liquid or tar is retained in the lower portion 17 of the separator tower 16, and in order to effectively cool the entering products from the coil, some of this tar may be drawn through the line 32^a and be circulated by pump 32^b through a cooler 32^c and returned through line 32^d. The cooled tar rapidly cools the entering hot vapors.

The separator tower 16 may be provided above the opening of the line 14 thereinto with suitable baffle or fractionating plates 18. At an intermediate point in the flash tower, a draw-off plate 20 is provided, this plate being diagrammatically illustrated as an annular disk secured to the sides of the separator tower 16 and provided with a central vapor conduit 21 to permit the upward passage of vapors while retaining collected reflux and condensate on the plate. Part of this condensate may be permitted to overflow and return to the liquid 17. Above the draw-off plate 20 additional fractionating plates 22 are provided, and in the top of the

tower 16 there may suitably be located the heat exchange coils 23.

Fresh oil to be fed to the system may suitably be supplied through the line 24 to the heat exchange coils 23 in the top of the separator tower 16, thereby controlling the temperature of the vapors issuing from the tower, and may then pass through the valved line 25 to line 26, by which the oil is conducted to a distributor 27 in the lower portion of the separator tower below the draw-off plate 20. If desired, additional oil to be fed into the system may be supplied to the line 26 through the valved line 28 or excess feed used for cooling at the top of the tower may be drawn off through the same valved line 28. As will be more fully pointed out hereinafter, the portions of the feed stock which are to be supplied to the heating coils are completely vaporized in the lower portion of the separator tower, the vapors pass upwardly through the vapor conduit 21 in the draw-off plate 20. The desired constituents of the stock, together with reflux condensate from the vapors issuing from the heating coil, are collected on the draw-off plate 20, withdrawn by the hot oil pump 29 and charged by the latter to the line 12 entering the heating coil.

Vapors uncondensed in the tower 16 pass out through the vapor line 30 to a suitable condenser 31 or, if desired, to a fractional condenser. The heavy liquid or tar collected in the lower portion 17 of the separator tower 16, may be withdrawn as desired through the valved line 32, and passed through suitable coolers or heat exchangers (not shown), as desired.

In carrying out the invention, the oil or composite feed which is completely vaporizable and is delivered to the heating coil through the line 12 is heated to effect its rapid vaporization and subsequent high temperature cracking of the vapors to as great an extent as possible. In order to secure the results which we desire to obtain, the oil is heated with a coil outlet pressure of from 100 to 400 lbs., to an outlet temperature of from 850 to 975° F., typical operating conditions being a pressure of about 175 to 180 lbs. and a temperature of about 925° F.

In the heating operation, the oil is brought from a temperature below that at which active cracking takes place, and at which vaporization begins, to a high cracking temperature approximating the desired outlet temperature at a rapid rate, so that cracked products in the gasoline boiling point range which are formed before the oil reaches a temperature of 850° F. bear a low ratio to the total quantity of such products formed in the operation, say, less than 15% of the gasoline. The proportion of liquid phase cracking is thus minimized since more than 85% of the gasoline produced in the opera-

tion is produced at temperatures within the range of from about 850° F. to about 975° F. A suitable routing of the oil is illustrated diagrammatically in connection with the furnace 5 in Fig. 1. Such a furnace may have 10 for example, 18 horizontal rows of tubes of 16 tubes each. The composite feed enters the top row, passes downwardly through the tubes of each successive row for five rows, and is then carried by the pipe 13 to the lowermost and hottest row and rises successively through the horizontal rows, making its exit through the line 14 at the thirteenth row from the bottom. In such an operation, with suitable control of the amount of cracking per pass, the temperature of the oil after passing through the top five rows and entering the tube 13 may be between 525 and 650° F., which is below the temperature at which appreciable cracking occurs. It then passes to the bottom row of tubes in the furnace in which there is the greatest heat input, and is rapidly raised to a temperature above 850° F., as by exposure to radiant heat as well as convection heat, or by other rapid heating means. It is substantially completely vaporized and brought to a high cracking temperature in the bottom two rows of tubes. In its continued travel through the remaining eleven rows of tubes, it may be gradually raised in temperature, being brought to an outlet temperature approximating 925° F.

In Fig. 5, the solid line curve designated I illustrates a typical operation of this character. In the chart there illustrated, the coordinates represent respectively the temperature of the oil and the tube rows of the heating furnace. It will be noted that in the first five rows of travel the oil is brought to a temperature of about 525° F. In the next two rows of travel, a temperature of about 850° F. is reached; at this point, in a typical example, the oil showed substantially no gasoline content. In its remaining travel through the furnace, it is gradually brought to a temperature of about 925° F. It will be noted that the oil is raised from 700° F. where cracking becomes appreciable to a temperature of about 850° F. very rapidly so that no cracked products or but a low proportion thereof are formed before the oil reaches 850° F.

In carrying out the operation with the heating conditions controlled as hereinbefore set forth, we have found that the most dependable measure of the time to which the oil is subjected to heat in the heating coil is the amount of cracked gasoline formed per pass, based upon the total composite feed to the coil, since the amount of cracking to gasoline effected is a measure of the time the oil is exposed to cracking temperature in the coil, the outlet temperature and approximate temperature gradient while under crack-

ing conditions being known. The amount of cracking to gasoline per pass which is secured is readily within the control of the operator, since it may be varied by varying the rate of feed under given temperature and pressure conditions. The cracking per pass may be decreased by increasing the rate of feed and vice-versa. The minimum desired cracking to gasoline per pass ranges from 2.5% at 100 lbs. pressure to 13% at 250 lbs. outlet pressure, at outlet temperatures of 850 to 975° F. for a product having a 1.5 cc. tetraethyl lead equivalent. For higher lead equivalent a higher cracking to gasoline per pass is necessary; thus for a 2.0 cc. product, the minimum ranges from 4% gasoline per pass at 100 lbs. to about 16.5% per pass at 400 lbs.

In Fig. 2 there is illustrated a modified form of apparatus for carrying out the present invention, in which the vapor products from the heating coil are discharged into a reaction chamber, in which the vapors are maintained at cracking temperature for a substantial further period of time and the capacity of the system increased.

Referring to Fig. 2 of the drawings, the numeral 40 designates a heating furnace containing heating coils 41, so constructed that the conditions of operation are similar to those described in connection with the heating coil of the form illustrated in Fig. 1. The feed to the coil enters through the line 42, first passing through an initial heating section 43 in which it is heated to a temperature below that at which vaporization and cracking begins. From this initial heating section 43, the oil passes through the line 44 to the lowermost row of tubes of the vaporizing and cracking section 45 in which it is rapidly vaporized and brought to the desired cracking temperature. The heated oil vapors pass out through the pipe 46 and are discharged into the lower portion of the reaction chamber 47 through an inlet device 48 above the level of any tar or liquid contained in the latter.

In the operation of the soaking drum, conditions are so maintained that the chamber is largely filled with vapor and so that there is a minimum of turbulence in the vapor in the chamber and a maximum temperature gradient between the vapor inlet and the vapor outlet. It has been found that these conditions can be most readily secured in an elongated vertical chamber. Although, it might appear that turbulence of the vapors in the drum could be most readily avoided by introducing vapors near the top of the chamber and removing them near the bottom, by reason of the increasing density of the vapors as they decrease in temperature, it has been found that such operation is not conducive to a maximum temperature gradient and a minimum of turbulence, but leads to

mixing and to even temperatures throughout the drum or chamber. It has been found advisable to introduce the heated vapors from the heating coil in the lower portion of the reaction chamber, removing vapors from the chamber at the top, because decreasing density due to cracking more than offsets increasing density due to cooling.

The distributing device 48 by which the vapors are introduced in the chamber is of a form providing a rapidly expanding discharge opening and is conducive to the introduction of the vapors at a low velocity to avoid excessive turbulence. In the form illustrated diagrammatically in Fig. 3, it consists of an expanding opening 49 below which is provided a baffle plate 50. The details of this inlet construction form the subject matter of the co-pending application of Snow, Serial No. 447,265, filed April 25, 1930.

The reaction chamber is suitably insulated to maintain the desired reaction temperature of the vapors, although it may be mildly heated for the purpose, if desired.

The vapors, after remaining in the reaction chamber 47 for a sufficient period to secure the desired conversion therein, are removed through the outlet line 51 and the formation of coke deposits in this line is prevented by any suitable means, for example, by the injection thereinto of fresh feed by means of the line 52 and nozzle 53. A suitable device for this purpose is shown more in detail in the co-pending application of Snow, Serial No. 428,431, filed February 14, 1930. The stock thus introduced passes off with the vapors from the reaction chamber through the line 51.

By thus introducing the heated products from the heating coil into the lower portion of vertical reaction chamber without substantial turbulence and removing the vapors from the top, it has been found possible to secure a slow and progressive movement of the vapors through the reaction chamber, with a high temperature gradient indicating the lack of turbulence therein. The difference in temperature between the vapors in proximity to the inlet and those in proximity to the outlet should be at least 10 to 15°; and in a reaction chamber, for example, six feet in diameter and forty feet high, it has been found possible to secure a temperature gradient of 30° and higher in the vapor. The tar, if any is present, is removed from the reaction chamber through an outlet 54, which projects upwardly a short distance into the reaction chamber from its lowermost portion and limits the level of tar. In order to prevent coke formation at this outlet and avoid consequent stoppage of flow of heavy liquid or tar, the outlet is surrounded by a coil 55, to which a suitable cool-

ing medium is supplied through the line 56, the liquid or medium thus supplied leaving the coil 55 through the line 57. This cooling medium or liquid may suitably be a portion of the fresh hydrocarbon oil fed to the system, supplied to the inlet line 56 through the line 58. After leaving the coil 55 through the line 57, the somewhat heated oil may pass through the line 59 to the line 52 and the nozzle 53 directed towards the vapor outlet in the reaction chamber.

The vapors pass out of the reaction chamber through the line 51 and pressure release valve 61 into the lower portion of the fractionating column 60, being joined before entering the latter by liquid products or tar withdrawn from the reaction chamber through line 54 and pressure release valve 62. At an intermediate point in the fractionating column 60 there is provided a suitable reflux draw-off plate 63 as shown in Fig. 4, provided with a vapor conduit 64, so that vapors from the lower portion of the column may ascend into the upper portion to be fractionated therein. A plurality of fractionating plates of any suitable type, 65, are provided in the column above the point of admission of the vapors and liquid from the reaction chamber. Above the draw-off plate in the column 63 there are likewise provided a plurality of suitable fractionating plates 66, and in order to secure additional cooling action in the fractionating column, suitable heat exchange coils 67 and 68 are provided therein, the former being near the vapor outlet of the column, and the latter at an intermediate point therein. A suitable cooling medium, such as the fresh feed to be supplied to the system, may enter the coil 67 through the line 69. After passing through the coil, it leaves the latter through line 70 and enters the coil 68, out of which it passes through the line 71, and the line 58 to the coil 55 surrounding the liquid outlet 54 from the reaction chamber 47 as hereinbefore described.

Reflux condensate formed from the vapors which enter the fractionating column and which are derived from the vapor products of reaction and the vaporized fresh feed introduced into the reaction chamber 47, are withdrawn from the draw-off plate 63 in the column 60 through the line 72 and discharged into the stripping tower 73 as hereinafter further described. Liquid products separated in the lower portion of the column 60 collect therein and may be withdrawn through the valved line 74. Uncondensed vapors of the desired distillate product pass out of the column 60 through the line 75 to a condenser 76 of any suitable type.

The condensed products discharged through the line 72 into the tower 73 are subjected to the stripping action of steam therein. A pool of such products is collected in the lower

portion of the tower 73, as at 77 and steam is introduced thereto through the line 78. The steam and vapors stripped from the liquid pass upwardly through the tower in countercurrent to the descending liquid condensed products, being intimately contacted therewith by the fractionating plates 79, which may be of any suitable type. The vapors and steam leaving the tower 73 pass out through the line 80 and enter the lower portion of the column 60, suitably above the line 72. The stripped condensate, which forms the composite feed stock to the heating coil, is withdrawn through line 81 and forced by pump 82 through line 83 to the line 42.

In the operation of the modified form of construction as shown in Fig. 2, the composite feed to the heating coils, derived as herein-after set forth, is supplied through the line 42 to the initial heating section 43, wherein it is brought to an elevated temperature below its vaporizing and cracking temperature. It then passes through the line 44 to the vaporizing and cracking section of the furnace, 45, wherein it is subjected to rapid heating to completely vaporize it, rapidly bringing it to the desired cracking temperature to effect the desired amount of cracking.

In heating the oil in the pipe still 40, the same principles are employed as in the pipe still 7 in connection with the first form of apparatus illustrated. However, in the modified form of apparatus, since a part of the desired cracking is effected in the reaction chamber 47, less cracking per pass is necessary in the pipe still, the through-put is correspondingly increased and the temperature gradient in the coil therefore varies somewhat from that which is obtained when the entire cracking desired is secured in the heating coil. This is illustrated by the broken line graph-II in Fig. 5, which represents a suitable temperature gradient secured in the pipe still of the lay-out of Fig. 2, which is similar to that of Fig. 1, but with the routing of the oil modified so that it passes downwardly successively through the top eleven rows, then is carried down to the bottom row and rises upwardly through the remaining seven rows. By this routing, it will be seen from the graph that the oil is gradually brought to a temperature below 700° F., at which appreciable cracking begins. It is brought from this temperature to a high cracking temperature of about 860° in traveling through two rows of tubes, whereby the low temperature cracking of the liquid oil is minimized, and the oil is subsequently brought to an outlet temperature of about 925° before entering the reaction chamber 47.

The vaporized products are then discharged through the line 46 into the vertical reaction chamber 47 through the distributor 48 in the lower portion thereof, this distributor having an outwardly flared opening as hereinbefore

- described, so as to reduce the velocity of the flow of the vaporized material and prevent turbulence in the reaction chamber. In general, no appreciable quantity of tarry liquid is present. The level, when present, is held low, and the discharge opening 48 of the pre-heater outlet pipe 46 is preferably disposed a slight distance above the limit of level of liquid, when present.
- 10 The vapors ascend slowly and without substantial turbulence through the reaction chamber to the vapor outlet 51. The lack of substantial turbulence is indicated by the temperature gradient in the reaction chamber, which should be a minimum of 10° to 15° F., with 5% or more of cracking to gasoline (based on the composite feed to the coil) taking place in the reaction chamber. Thus, in a typical operation, with 175 to 180 lbs. 15 pressure in the reaction chamber, the outlet temperature of the heating coil about 925° F., the total cracking per pass based on the composite feed from 20 to 22%, of which approximately half is effected in the reaction chamber, a temperature gradient of about 20 30° has been secured in the vapors in the drum, the temperature of the vapor near the discharge opening 49 being about 890° F. and that of the vapor near the outlet 51 being 25 about 860° F. Such a temperature gradient indicates little or substantially no turbulence in the vapors in the reaction chamber and an appreciable stratification thereof, a slow, even progress toward the vapor outlet and 30 optimum conditions for vapor phase cracking.
- The general conditions of operation in the modified form of apparatus illustrated in Fig. 2, with respect to relative temperatures and pressures of operation and of cracking per pass are substantially the same as those herein described in connection with the lay-out illustrated in Fig. 1, the operation being so controlled that at least one-fourth and 35 preferably not more than three-fourths of the desired cracking per pass is effected in the reaction chamber 47. In general, the cracking per pass is advantageously approximately equally divided between the heating coil and the reaction chamber 47 and at least 5% per pass is effected in the latter.
- Vapors are withdrawn from the reaction chamber through the line 51 and tarry liquid, if any, from the lower portion thereof 40 through the line 54, as hereinbefore stated. Part of the fresh feed supplied to the system, which may have been preheated to some extent in the coils 67 and 68 in the fractionating column 60, may be passed through the 45 helical coil 55 which surrounds the tar outlet 54 in the reaction chamber 47 and is then discharged through outlet 53 directly into the body of vapors therein. It mixes with the outgoing cracked vapors and enters the 50 lower portion of the fractionating column 60 together with the tarry liquid from the reaction chamber. The pressure on the cracked vapors may be substantially reduced on passing through valve 61, preferably to a value of from 10 to 60 lbs. gauge.
- The vapors of the cracked products, which include the desired distillate products and heavier constituents, together with the vapors of the feed stock introduced into the reaction chamber separate from liquid in the lower portion of the column 60, entrained liquid being separated from the vapors by the action of the plates 65. The vapors rise through the vapor conduit 64 in the draw-off plate 63 and enter the upper portion of the fractionating column, in which the heavier constituents of the vapors are condensed. The lighter constituents, including the desired distillate products, pass out through the line 75 to any suitable condenser or fractional condensing device 76.
- The condensate formed in the upper portion of the column, which includes the vaporized constituents derived from the cracking operation heavier than the desired gasoline product as well as the constituents of the feed stock, collects in the draw-off plate 63, passes out through the line 72 and enters the stripping tower 73, descending downwardly through fractionating plates 79 countercurrent to stripping steam and vapors. A pool of the composite liquid, which forms the feed for the heating coils and reaction chamber, collects in the lower portion of the stripping tower, and steam from the line 78 is passed into it to effect the desired stripping. The steam and vapors from the stripping operation pass through the line 80 into the lower portion of the column 60. The stripped composite feed is withdrawn from the stripping tower 73 through the line 81 by the hot oil pump 82 and discharged through line 83 into the inlet line 42 of the heating coil 41.
- In carrying out the operation, the conditions with reference to temperature, pressure and cracking to gasoline per pass (based on a total composite feed) are substantially similar to those maintained in operating in the type of lay-out illustrated in Fig. 1. That is, the pressure in the reaction chamber 47 is maintained between 100 lbs. and 400 lbs., the temperature at the outlet of the coil and in the reaction chamber being from 825 to 975° F., and the minimum amount of cracking to gasoline per pass within this range of temperatures and pressures varying from about 13% per pass at 250 lbs. to about 2.5% per pass at 100 lbs. for a product having 1.5 cc. tetraethyl lead equivalent. Of this cracking, from one-fourth to three-fourths may be effected in the heating coil 41 and the remainder in the reaction chamber 47, being ordinarily about equally divided between the two. It is thus apparent that by operating

with a layout as illustrated in Fig. 2, with a coil of a given size, a much greater distillate production can be secured than with the form of apparatus illustrated in Fig. 1.

- 5 The following specific example illustrates the operation of the layout such as that of Fig. 2 in accordance with the present invention.

The composite feed drawn from the 10 stripping tower 73 reaches the heating coil 41 at a temperature of about 550° and a pressure sufficient to give a coil outlet pressure and a pressure in the reaction chamber of 175 to 180 lbs. In passing through the coil, 15 the oil is heated to about 925° F. and is then discharged into the reaction chamber, the operation of which has been hereinbefore described. In the reaction chamber, a temperature gradient of from 890° F. to about 860° 20 F. is maintained and the rate of flow of the oil is so controlled that a total cracking to gasoline of 20 to 22% per pass on the total composite feed passing through the coil is secured, approximately half of this being 25 secured in the heating coil. The fresh feed, which amounts to about one-fourth of the total composite feed to the coil, is supplied in the reaction chamber and vaporized there as hereinbefore described. A relatively small 30 proportion of the condensed and separated tarry liquid is maintained in the drum. The products are discharged into the column 60 as hereinbefore described, in which the vapors are cooled to about 325° F. before leaving to 35 enter the condenser.

The liquid products secured in such an operation are, based on the fresh feed, from 69 to 70% of a gasoline motor fuel having an anti-knock value equivalent to 2 cubic centimeters of tetra-ethyl lead per gallon of Mid-Continent gasoline, and about 20% of an 8° A. P. I. gravity tarry liquid.

Within the range of temperatures and pressures herein set forth for operation in 45 accordance with the present invention, decrease in pressure, increase in temperature or increase in percentage of cracking to gasoline per pass tend to increase the anti-knock value of the fuel product. Thus, at 100 lbs. 50 pressure, and about 950° F. coil outlet temperature, in an operation without the reaction chamber, with about 20% cracking per pass, a product having a 2.0 cc. lead equivalent is secured, and by raising the proportion 55 of cracking to gasoline per pass to about 26%, a product having a lead equivalent of about 2.5 is secured. The total yield of gasoline is, however, somewhat decreased and the capacity of the unit is correspondingly decreased. 60 In a similar operation at 250 lbs. pressure, 875° F., and about 25% cracking to gasoline per pass, a product of about 1.5 cc. lead equivalent is obtained; at 925° F. outlet temperature and the same pressure, with about 65 26.5% cracking to gasoline per pass, a prod-

uct of 2.0 cc. lead equivalent is secured; and at the latter temperature and pressure, on raising the per cent of cracking to gasoline per pass to about 33%, a product of 2.5 cc. lead equivalent is secured. 70

Certain of the features of apparatus and operation herein set forth are separately described and claimed in the application of Snow, Serial No. 428,430, filed February 14, 1930; Snow, Serial No. 428,431, filed February 14, 1930, and Snow, Serial No. 447,265, filed April 25, 1930. 75

Although the invention has been set forth in connection with various specific details of apparatus and of operation, and is especially adapted for operation in connection therewith, it is not intended that these shall be regarded as limitations upon the scope of the invention, except in so far as included in the accompanying claims. 80

We claim:

1. The method of producing a low boiling motor fuel product having anti-knock characteristics which comprises rapidly heating a higher boiling substantially completely vaporizable hydrocarbon oil from a temperature below a substantial cracking temperature to vaporize it and bring the vapors to a cracking temperature between about 850 and about 975° F., holding the oil vapors at a temperature between about 850 and about 975° F. while maintaining thereon a pressure from about 100 lbs. to about 400 lbs. for a period of time sufficient to secure a minimum proportion per pass of cracked product of the desired characteristics ranging from about 2.5% at 100 lbs. to about 13% at 400 lbs. of the total material treated, said rapid heating of the oil being accomplished at such a rate that at least 85% of the said total conversion per pass is effected at the said temperatures between about 850 and about 975° F., thereby securing a gasoline motor fuel product having an anti-knock equivalent of at least 1.5 cc. of tetraethyl lead per gallon of Mid-Continent gasoline. 105

2. The method of producing a low boiling motor fuel product having anti-knock characteristics which comprises rapidly heating a higher boiling substantially completely vaporizable hydrocarbon oil from a temperature below a substantial cracking temperature to vaporize it and bring the vapors to a cracking temperature between about 850 and about 975° F., holding the oil vapors at a temperature between about 850 and about 975° F. while maintaining thereon a pressure from about 100 lbs. to about 250 lbs. for a period of time sufficient to secure a minimum proportion per pass of cracked product of the desired characteristics ranging from about 2.5% at 100 lbs. to about 13% at 250 lbs. of the total material treated, said rapid heating of the oil being accomplished at such a rate that at least 85% of the said 115

total conversion per pass is effected at the said temperatures between about 850 and about 975° F., thereby securing a gasoline motor fuel product having an anti-knock equivalent of at least 1.5 cc. of tetraethyl lead per gallon of Mid-Continent gasoline.

3. The method of producing a low boiling motor fuel product having anti-knock characteristics which comprises rapidly heating a higher boiling substantially completely vaporizable hydrocarbon oil, comprising a mixture of fresh charging stock and recycle stock, from a temperature below a substantial cracking temperature to vaporize it and bring the vapors to a cracking temperature between about 850 and about 975° F. while maintaining thereon a pressure from about 100 lbs. to about 400 lbs. for a period of time sufficient to secure a minimum proportion per pass of cracked product of the desired characteristics ranging from about 2.5% at 100 lbs. to about 13% at 400 lbs. of the total material treated, said rapid heating of the oil being accomplished at such a rate that at least 85% of the said total conversion per pass is effected at said temperatures between about 850° F. and about 975° F., fractionating the cracked vapor products to separate as reflux condensate undesired higher boiling constituents thereof, separately collecting the desired fractionated vapors, and admixing said reflux condensate with fresh oil and subjecting the said mixture to the aforesaid cracking operation.

4. The method of producing a low boiling motor fuel product having anti-knock characteristics which comprises forcing a higher boiling substantially completely vaporizable hydrocarbon distillate oil in a restricted stream through a heating coil, applying heat thereto at a rapid rate to raise the oil from a temperature below a substantial cracking temperature and to rapidly vaporize the oil and bring the vapors to a cracking temperature between about 850 and about 975° F., and maintaining the vapors at a temperature between about 850 and about 975° F. and at a pressure of from about 100 lbs. to about 400 lbs. for a period of time sufficient to secure a proportion of cracked products of the desired characteristics based upon the total material treated in a minimum proportion per pass varying from about 2.5% at 100 lbs. to about 13% at 400 lbs., said rapid heating of the oil being accomplished at such a rate that at least 85% of the said total conversion per pass is effected at the said temperatures between 850 and 975° F.

5. The method of producing a low boiling motor fuel product having anti-knock characteristics which comprises forcing a higher boiling substantially completely vaporizable hydrocarbon distillate oil in a restricted stream through a heating coil, applying heat thereto at a rapid rate to raise the oil from

a temperature below a substantial cracking temperature and to rapidly vaporize the oil and bring the vapors to a cracking temperature between about 850 and about 975° F., and maintaining the vapors at a temperature between about 850 and about 975° F. and at a pressure of from about 100 lbs. to about 400 lbs. for a period of time sufficient to secure a proportion of cracked products of the desired characteristics based upon the total material treated in a minimum proportion per pass varying from about 4% at 100 lbs. to about 16.5% at 400 lbs., said rapid heating of the oil being accomplished at such a rate that at least 85% of the said total conversion per pass is effected at the said temperatures between 850 and 975° F.

6. The method of producing a low boiling motor fuel product having anti-knock characteristics which comprises rapidly heating a higher boiling substantially completely vaporizable distillate oil to raise the oil from a temperature below a substantial cracking temperature to rapidly and completely vaporize the oil and bring the vapors to a temperature of about 900° F., maintaining the vapors at a temperature above 850° F. but not above about 900° F. and a pressure of about 175 to 180 lbs. to convert at least 20% thereof into the desired motor fuel product, said conversion operation being so controlled that at least 85% of the total conversion of the oil into desired motor fuel product is effected at temperatures above 850° F., thereby securing a motor fuel product having an anti-knock equivalent of at least 2 cc. tetraethyl lead per gallon of Mid-Continent gasoline.

7. The method of producing a low boiling motor fuel product having anti-knock characteristics which comprises passing a higher boiling substantially completely vaporizable hydrocarbon oil through a heating coil while maintaining at the outlet thereof a pressure of from about 100 to about 400 lbs., rapidly heating the oil in its flow through the coil to vaporize the oil and raise it from a temperature below a temperature of 700° F. and bring the vapors to a cracking temperature of at least 850° F. and not substantially above 975° F., maintaining the vapors at said cracking temperature above 850° F. and not above 975° F. to secure a total cracked product in the gasoline range of boiling points per pass in a minimum amount ranging from about 2.5% at 100 lbs. to about 13% at 400 lbs. of the total material treated, said conversion operation being so controlled that at least 85% of the total conversion per pass is effected at temperatures of at least 850° F., whereby a product having high anti-knock properties is produced.

8. The method of producing a low boiling motor fuel product having anti-knock characteristics which comprises passing a higher

- boiling substantially completely vaporizable distillate oil through a heating coil while maintaining an outlet pressure on said coil of from about 100 to about 400 lbs., heating it during its passage therethrough from below a substantial cracking temperature to rapidly vaporize the oil and bring the vapors to a cracking temperature above about 850° F. and not substantially above about 975° F., continuing the heating of the oil while in flow through said coil to maintain the oil at a temperature between about 850° F. and about 975° F. and to secure a total amount per pass of the desired cracked product in the gasoline range of boiling points in a minimum amount ranging from about 2.5% at 100 lbs. to about 13% at 400 lbs. of the total material treated, said heating of the oil being so controlled that more than 85% of the desired amount of cracked product in the gasoline range of boiling points is formed while the oil is at temperatures above about 850° F., thereby producing a motor fuel product in the gasoline range of boiling points having a high anti-knock value.
9. The method of producing a low boiling motor fuel product having anti-knock characteristics which comprises flowing a higher boiling substantially completely vaporizable distillate oil through a coil, maintaining a pressure on the outlet thereof of from about 100 to about 400 lbs., heating the said oil in its flow through the coil from below a substantial cracking temperature to rapidly and completely vaporize the oil and bring the vapors to a cracking temperature above 850° F. but not above 975° F., passing the heated vapors into an enlarged chamber and causing them to travel slowly therethrough while maintaining therein a pressure approximating the outlet pressure on the coil and a temperature above 850° F. but not above 975° F., and retaining the vapors in the coil and the enlarged chamber at said cracking temperature for a sufficient period of time to secure a conversion thereof into motor fuel products in the gasoline boiling point range in a minimum amount per pass ranging from about 2.5% at 100 lbs. pressure to about 13% at 400 lbs., the heating of the oil in said coil being accomplished at such a rate that less than 15% of the total conversion per pass is effected at temperatures below 850° F., whereby a motor fuel product in the gasoline boiling point range having a high anti-knock value is secured.
10. The method of producing a low boiling motor fuel product having anti-knock characteristics which comprises flowing a higher boiling substantially completely vaporizable distillate oil through a coil, maintaining a pressure on the outlet thereof from about 100 to about 400 lbs., heating the said oil in its flow through the coil from below a substantial cracking temperature to rapidly and completely vaporize the oil and bring the vapors to a cracking temperature above 850° F. but not above 975° F., passing the heated vapors into an enlarged chamber and causing them to travel slowly therethrough while permitting stratification of the vapors, maintaining within the chamber a pressure approximating the outlet pressure on the coil and a temperature above 850° F. but not above 975° F., and retaining the vapors in the coil and the enlarged chamber at said cracking temperature for a sufficient period of time to secure a conversion thereof into motor fuel products in the gasoline boiling point range in a minimum amount per pass ranging from about 2.5% at 100 lbs. pressure to about 13% at 400 lbs., the heating of the oil in said coil being accomplished at such a rate that less than 15% of the total conversion per pass is effected at temperatures below 850° F., whereby a motor fuel product in the gasoline boiling point range having a high anti-knock value is secured.
11. The method of producing a low boiling motor fuel product having anti-knock characteristics which comprises passing a higher boiling substantially completely vaporizable distillate oil through a coil while maintaining an outlet pressure thereon of about 100 lbs. to about 400 lbs., heating the oil in its flow through the coil from below a substantial cracking temperature to rapidly bring it to cracking temperature and to rapidly and completely vaporize the oil and heat the vapors to a cracking temperature above about 850° F. but not above about 975° F., then passing the vapors into an enlarged chamber and causing them to pass slowly therethrough while maintaining therein a pressure of from 100 lbs. to 400 lbs. and a temperature above about 850° F. but not substantially above about 975° F., said vapors being maintained at a cracking temperature above 850° F. but not substantially above 975° F. in the coil and enlarged chamber for a sufficient period to convert into motor fuel products in the gasoline boiling range a desired portion thereof in a minimum amount per pass ranging from about 2.5% at 100 lbs. pressure to about 13% at 400 lbs., the vapors being maintained in the enlarged chamber a sufficient period to effect from about one-fourth to about three-fourths of said cracking therein, the said heating of the oil in said coil from below a cracking temperature to a temperature above about 850° F. being conducted at such rate that substantially less than 15% of the total motor fuel products formed in the coil and enlarged chamber are produced at temperatures below 850° F.
12. The method of producing a low boiling motor fuel product having anti-knock characteristics which comprises forcing a substantially completely vaporizable distillate hy-

- drocarbon oil heavier than gasoline through a coil, heating the oil in its passage through the coil from below a substantial cracking temperature to rapidly and completely vaporize the oil and bring the vapors to an outlet temperature of about 925° F. while maintaining an outlet pressure of about 175 to 180 lbs. gauge thereon, the oil vapors being retained within the coil for a period sufficient to produce a total conversion thereof into vapors of products of the boiling point range of gasoline amounting to at least about 20% per pass, thereby forming a motor fuel product having an anti-knock value of about 15 2 cc. tetraethyl lead per gallon, the said heating of the oil in said coil being so controlled that the oil is brought from below cracking temperature to a temperature of about 850° F. while effecting less than 15% of the total 20 conversion per pass into the desired anti-knock motor fuel product.
13. The method of producing a low boiling motor fuel product having anti-knock characteristics which comprises forcing a substantially completely vaporizable distillate hydrocarbon oil heavier than gasoline through a coil maintained under an outlet pressure of about 175 to 180 lbs., heating the oil in its flow through the coil from below a substantial cracking temperature to rapidly and completely vaporize the oil and bring the vapors to a cracking temperature above 850° F., continuing the heating of the oil vapors to secure a coil outlet temperature of about 30 925° F., the oil vapors being maintained at a cracking temperature exceeding 850° F. but not above 925° F. to secure a conversion thereof into gasoline-like products of about 15% per pass, the said heating of the oil in said coil being so controlled that the oil is brought from below cracking temperature to a temperature of about 850° F. while effecting less than 15% of the total conversion per pass into the desired motor fuel product.
14. The method of producing a low boiling motor fuel product having anti-knock characteristics which comprises passing a higher boiling substantially completely vaporizable distillate oil through a coil maintained under an outlet pressure of about 175 to 180 lbs., heating the oil in passage through the coil from below a substantial cracking temperature to rapidly and completely vaporize the oil and bring the oil vapors to a cracking temperature above 850° F., continuing the heating of the oil in its flow through the coil to secure an outlet temperature thereof of about 925° F., discharging the oil vapors into an enlarged chamber, said chamber being largely filled with vapors, causing the vapors to pass slowly through said chamber without turbulence and at a temperature exceeding 850° F. but not above 925° F., the oil vapors being maintained at cracking temperature 60 above 850° F. for a period sufficient to secure a total conversion thereof into gasoline-like products of about 15%, the said heating of the oil in said coil from below a cracking temperature to a temperature above 850° F. being conducted at such a rate that less than 15% of the total motor fuel products formed in the coil and enlarged chamber are produced at temperatures below 850° F., thereby forming hydrocarbons in the gasoline range of boiling points having a high anti-knock value.
15. The method of producing a low boiling motor fuel product having anti-knock characteristics which comprises rapidly heating a higher boiling substantially completely vaporizable hydrocarbon oil from a temperature below a substantial cracking temperature to vaporize it and bring the vapors to a cracking temperature between about 850 and about 975° F., holding the oil vapors at a temperature between about 850 and about 975° F. while maintaining thereon a pressure from about 100 lbs. to about 400 lbs. for a period of time sufficient to secure a minimum proportion per pass of cracked product of the desired characteristics ranging from about 2.5% at 100 lbs. to about 13% at 400 lbs. of the total material treated, said rapid heating of the oil being accomplished in a restricted passage located in a radiant heating zone and at such a rate that at least 85% of the said total conversion per pass is effected at the said temperatures between about 850 and about 975° F., thereby securing a gasoline motor fuel product having an anti-knock equivalent of at least 1.5 cc. of tetraethyl lead per gallon of Mid-Continent gasoline.
16. The method of producing a low boiling motor fuel product having anti-knock characteristics which comprises rapidly heating a higher boiling substantially completely vaporizable hydrocarbon oil from a temperature below a substantial cracking temperature to vaporize it and bring the vapors to a cracking temperature between about 850 and about 975° F., holding the oil vapors at a temperature between about 850 and about 975° F. while maintaining thereon a pressure from about 100 lbs. to about 250 lbs. for a period of time sufficient to secure a minimum proportion per pass of cracked product of the desired characteristics ranging from about 2.5% at 100 lbs. to about 13% at 250 lbs. of the total material treated, said rapid heating of the oil being accomplished in a restricted passage located in a radiant heating zone and at such a rate that at least 85% of the said total conversion per pass is effected at the said temperatures between about 850 and about 975° F., thereby securing a gasoline motor fuel product having an anti-knock equivalent of at least 1.5 cc. of tetraethyl lead per gallon of Mid-Continent gasoline.

17. The method of producing a low boiling motor fuel product having anti-knock characteristics which comprises passing a higher boiling substantially completely vaporizable hydrocarbon oil through an elongated confined heating zone of restricted cross-section and heating it while in transit therethrough from a temperature below a substantial cracking temperature to vaporize it and rapidly bring the vapors to a cracking temperature of about 850° F., continuing the heating of said vapors to bring them to a temperature of from about 875 to about 950° F., and holding the oil vapors at a temperature between about 875 and about 950° F. while

maintaining thereon a pressure of from about 100 lbs. to about 250 lbs. to secure a minimum conversion thereof into gasoline-like products of about 20% per pass, the said rapid heating of the oil being so controlled that at least 85% of the total conversion per pass into the desired motor fuel product is effected while the oil is at a temperature above about 850° F., thereby securing a gasoline motor fuel product having an anti-knock equivalent of at least 1.5 cc. of tetraethyl lead per gallon of Mid-Continent gasoline.
